OVERHEAD RAIL CLEANER

Louis W. Kahn, Cincinnati, Ohio

Application February 4, 1936, Serial No. 62,327

8 Claims. (Cl. 15—21)

The present invention relates to a cleaning device for overhead rails or tracks such as are used in abattoirs or other preparing plants, for conveying carcasses or other food products which should be protected from scale, dirt, or rust particles that accumulate upon the overhead rails and drop therefrom. The cleaning of such rails has heretofore been accomplished by the use of hand scrapers or brushes, in a laborious manner.

10 An object of the invention is to minimize the labor and expense of cleaning overhead rails, and to greatly reduce the time required for the cleaning operation.

Another object of the invention is to provide a simple, effective, and easily manipulated machine for performance of the rail cleaning operation.

These and other objects are attained by the means described herein and disclosed in the accompanying drawing, in which:

20 Fig. 1 is an elevational view of the device of the invention.

Fig. 2 is a side view of the Fig. 1 device.

With reference to the drawing, the character 3 indicates a high overhead rail which is not conveniently within the reach of a workman whose duty is to keep the rail free of accumulated dirt, rust particles and the like. In many establishments, particularly packing houses and the like, the equipment comprises several miles of overhead rails or tracks which are subject to corrosion and the accumulation of dirt and moisture, so that the rails or tracks must be cleaned periodically to prevent the foreign matter from dropping onto the carcasses or other food products transported by means of carriages that operate over the rails. The cleaning of the rails or tracks has heretofore been a laborious procedure, which now has been obviated by means of the present invention.

40 The cleaning device of the present invention comprises a carriage which includes a pair of hangers 4, each of which is provided with a flanged wheel 5 adapted to ride upon the rail. Suspended from each hanger by means of a swivel or pivot 6, is a guide bar or rod 7, said bars or rods being maintained in parallel relationship as will be explained. A pair of connecting bars 8 have their upper ends 9 secured to the lower ends 10 of the guide bars or rods 7 in any suitable manner, such as by means of screws or other fasteners 12. The connecting bars have spaced lower ends 13 which depend downwardly to a location substantially within the reach of an operator of the rail cleaner.

55 The guide bars or rods 7 provide a support for

a vertically shiftable rail cleaner support 14 which carries a motor 22 and a pair of rail cleaners 15 and 16, which cleaners may be in the form of rotatable brushes, each of which is driven by the motor 22. The brushes may be rotated in any suitable manner, one form of drive means being shown in the accompanying drawing. As shown, each rotating brush has a shaft 17, one of which carries a gear 18, and the other of which carries a gear 19, these gears being meshed with a pinion 20 on the motor shaft 21. It will be observed by reference to Fig. 2 that the brushes 15 and 16 are slightly spaced apart so that when they are elevated toward the rail 3, the rail will be received therebetween.

To facilitate elevating and lowering of the assembly 14—15—16—22, the rail cleaning means support 14 is seated upon a pair of springs which surround the guide bars or rods 7 and rest against the lower ends 10 thereof. As illustrated in the drawing, the springs are of the compression type, but it is to be understood that tension type springs may be employed to suspend the motor assembly from the upper ends of the guide rods 7, if desired. The counterbalancing means just described might also include a weight acting in opposition to the gravitational tendency of the motor assembly, as will readily be understood.

Depending from the motor 22 is a hand piece 24 which may be in the form of a shaft or rod, 30 said piece 24 being extended downwardly to a location at which an operator may conveniently grasp it for pushing or pulling the device along the rail 3 during the cleaning operation. The hand piece is to be fixed relative to the motor 35 assembly in any suitable manner, such as by means of a bracket 25. At or near the lower end of the hand piece is mounted an electrical switch 26 to which the power line 27 is connected, said switch constituting a means for the control of the 40 motor 22.

It is to be understood that the motor control means 26 may be located at any other location within easy reach of the operator of the cleaning device.

The means for elevating and lowering the motor assembly and the cleaning means 15 and 16 to the operative position against the sides of the rail, and to the inoperative position shown in Figs. 1 and 2, may comprise a lever or other 50 manipulating means 28 located within the reach of the operator. As shown in the present form of device, the lever or manipulating means 28 has a forked end to provide arms 29 and 30, through which passes a suitable pivot element 31 55

whereby the lever is pivoted upon the hand piece 24. An extension 32 on each of the arms 29 and 30 is pivoted as at 33 upon the lower ends 13 of the connecting bars 8, so that rotation of 5 the lever or manipulating means 28 about the pivot 31 will shift the hand piece and the motor assembly bodily upwardly toward the rail. In the upper or operative position of the motor and brush assembly, the lever 28 assumes a dead center position at which the motor and brush assembly are locked or latched in the operative rail 10 cleaning position. The hand piece or shaft 24 may be provided near its lower end with a suitable extension or handle 34, which the operator 15 may grasp in guiding the device along the curved sections of the overhead rail. The member 34 is fixedly mounted upon the hand piece 24.

In order that the cleaning means or brushes 20 may operate effectively upon both vertical faces 20 of the rail 3, a self-adjusting equalizing means is provided. Said means may be associated with the hangers 4, and may comprise an extension 35 disposed at right angles to the hanger and having formed therein an elongated slot 36 in which 25 the pivot 6 may shift. As is clearly indicated by Fig. 2, the pivot 6 may shift laterally in the slot 36, at right angles to the rail 3, so that an upward projection of the brushes 16 and 17 about the rail will automatically serve to shift the pivot 30 6 relative to the slot 36, to a position at which each brush contacts the rail with equal force. Although only one form of equalizing means is disclosed, it is to be understood that other forms 35 may be employed, the simplest of which would be to elongate the axle 37 of the wheel 5, and permit the wheel to adjust itself along the length of such axle. As will be understood, the self-equalizing means whatever may be its form, will facilitate negotiating curved sections of the rail, by 40 maintaining equal forces of the brushes upon the opposite sides of the rail. In the embodiment shown, the swivel or pivot at 6 is transverse to or in right angular relationship with hanger wheel axis 37.

45 It is to be understood that the rail cleaners may take several forms, and may perform an abrading function or a scraping function, depending upon the nature of the accumulated material upon the rail. It is ordinarily found, however, that rotating wire brushes driven at a proper speed, will remove all ordinary accumulated material from the sides and the upper and lower surfaces of the rail.

As is evident, the device of the present invention 55 minimizes greatly the labor and expense of cleaning overhead rails, and reduces to a minimum the time required for the cleaning operation. The machine is simple, effective, and easily manipulated, and it performs the cleaning 60 operation more thoroughly than it can be performed using hand labor.

It is to be understood that various modifications and changes in the structural details of the device may be made, within the scope of the 65 appended claims, without departing from the spirit of the invention.

What is claimed is:

1. A cleaning device for the side faces of an 70 overhead rail which is normally out of reach of an operator, comprising in combination, a carriage including means for suspending it from such rail, a power actuated cleaning means supported by the carriage, a depending hand piece of such length as to be within easy reach of an operator, said hand piece being rigidly connected 75

with the carriage whereby movement of the carriage along the rail may be effected by the operator from a position beneath the rail, and a control means on the hand piece for control of the power actuated cleaning means. 5

2. A cleaning device for the opposed side faces of an overhead rail which is normally out of reach of an operator, comprising in combination, a carriage including means for suspending and moving it along such rail, a power actuated 10 cleaning means supported by the carriage, a depending hand piece of such length as to be within easy reach of an operator, whereby an operator may move the suspended carriage along the rail lengthwise thereof, and means carried by 15 the hand piece for selectively placing the cleaning means into and out of cooperative relationship with the rail.

3. A cleaning device for an overhead rail which is normally out of reach of an operator, comprising in combination, a carriage including means for suspending it from the rail for movement along such rail, a power actuated cleaning means embracing opposite surfaces of the rail and supported by the carriage beneath the rail, a depending hand piece of such length as to be within easy reach of an operator, and of such rigidity as to enable movement of the carriage along the rail by the operator, means carried by the hand piece for selectively placing the cleaning means into and out of cooperative relationship with the rail, and means operative upon disposition of the cleaning means to the operative position, to equalize the force of the cleaning means upon 30 opposite sides of the rail. 35

4. A cleaning device for overhead rails, comprising in combination, a carriage suspended from the rail to be cleaned, and means depending from the carriage to a location within the reach of an operator, for moving the carriage manually along the rail, a power actuated rail cleaning means supported by the carriage, and means for selectively placing the rail cleaning means into and out of contacting relationship with the rail, while the carriage remains suspended from the 45 rail.

5. A cleaning device for the opposed side faces of an overhead rail, comprising in combination, a carriage supported by the rail to be cleaned, and means within the reach of an operator for moving the carriage along the rail, a power actuated rail cleaning means supported by the carriage and embracing the opposed side faces of the rail, means for selectively placing the rail cleaning means into and out of contacting relationship 55 with the rail, while the carriage remains supported by the rail, and means operative upon disposition of the rail cleaning means to rail contacting position, for equalizing the force of contact of the cleaning means upon the faces of the 60 rail.

6. A cleaning device for the opposed side faces of a high overhead rail, comprising in combination, a carriage suspended from the rail to be cleaned and movable lengthwise of the rail, a rail 65 cleaning means comprising a pair of opposed brushes between which the rail is receivable, a rail cleaning means support mounted upon the carriage for vertical shifting movement, to dispose the brushes in operative and inoperative 70 positions relative to the rail, a hand piece associated with said support to extend downwardly to a position within the reach of an operator, whereby the carriage may be moved along the rail, means mounted upon the hand piece for 75

- selectively shifting the brushes to the operative and inoperative positions aforesaid, and means for power actuating the brushes while in contact upon the rail.
- 5 7. A cleaning device for the opposed side pieces of an overhead rail, comprising in combination, a carriage suspended from the rail to be cleaned and movable lengthwise of the rail, a pair of rail cleaning members spaced apart to receive the rail and to operate upon opposed faces thereof, a cleaning member support including a motor mounted upon the carriage for vertical movement, to dispose the cleaning members in operative and inoperative positions relative to the rail, a hand piece depending from the motor adapted to be grasped by an operator for moving the carriage along the rail, and means connected with said hand piece and carriage for bodily shifting the motor, the cleaning members, and the cleaning member support selectively toward and from the rail.
- 10 15. A hand piece adapted to be grasped by an operator for moving the carriage along the rail, and means for bodily shifting the motor, the cleaning members, and the cleaning member support selectively toward and from the rail.
- 15 20. 8. A cleaning device for overhead rails, com-

prising in combination, a carriage having rotatable supporting means whereby it may be supported by the rail to be cleaned and moved lengthwise of the rail, a pair of rail cleaning members spaced apart to receive the rail and to operate upon opposed faces thereof, a cleaning member support including a motor mounted upon the carriage for vertical movement, to dispose the cleaning members in operative and inoperative positions relative to the rail, a hand piece 5 depending from the motor adapted to be grasped by an operator for moving the carriage along the rail, and means connected with said hand piece and carriage for bodily shifting the motor, the cleaning members, and the cleaning member 10 support selectively toward and from the rail, axially of the hand piece, and means on said carriage for counterbalancing the weight of said bodily shiftable parts.
